Patented Oct. 2, 1956

178,892

PHOTOGRAPHIC SLIDE VIEWER

Samuel Lazerson, Cresskill, N. J., assignor to Interstate Photo Supply Corp., a corporation of New York

Application November 16, 1955, Serial No. 38,913

Term of patent 14 years

(Cl. D61—1)

Fig. 1

Fig. 2

Fig. 3

Fig. 4

Figure 1 is a perspective view of a photographic slide viewer embodying my new design;

Figure 2 is a left side elevational view thereof with adjustable focusing member extended;

Figure 3 is a top plan view of Figure 1; and

Figure 4 is a bottom plan view of Figure 2.

The back of the slide viewer is substantially plain.

I claim:

The ornamental design for a photographic slide viewer, substantially as shown and described.
